US0D1011313S

(12) **United States Design Patent** (10) Patent No.: **US D1,011,313 S**
(45) Date of Patent: ** Jan. 16, 2024

(54) **REMOTE CONTROL (WIRELESS)**

(71) Applicant: **SOMFY ACTIVITES SA**, Cluses (FR)

(72) Inventor: **Jonathan Tordjman**, Sevres (FR)

(73) Assignee: **SOMFY ACTIVITES SA**, Cluses (FR)

(**) Term: **15 Years**

(21) Appl. No.: **35/514,615**

(22) Filed: **Jun. 3, 2022**

(80) **Hague Agreement Data**

Int. Filing Date: **Jun. 3, 2022**

Int. Reg. No.: **DM/221629**

Int. Reg. Date: **Jun. 3, 2022**

Int. Reg. Pub. Date: **Jul. 1, 2022**

(30) **Foreign Application Priority Data**

Dec. 10, 2021 (EM) 008793608-0001

(51) **LOC (14) Cl.** **14-01**

(52) **U.S. Cl.**

USPC **D14/218**
